(57) **CLAIM**

The ornamental design for a rotary tool as shown and described.

DESCRIPTION

FIG. 1 is a perspective view of a rotary tool showing our new design;

FIG. 2 is a second perspective view of the rotary tool of FIG. 1;

FIG. 3 is a top plan view of the rotary tool of FIG. 1; FIG. 4 is a bottom plan view of the rotary tool of FIG. 1; FIG. 5 is a right side elevational view of the rotary tool of FIG. 1;

FIG. 6 is a left side elevational view of the rotary tool of FIG. 1;

FIG. 7 is a front elevational view of the rotary tool of FIG. 1; and,

FIG. 8 is a rear elevational view of the rotary tool of FIG. 1.

In the drawings, broken lines represent the environment of the claimed design and form no part of the claimed design.
